UNITED STATES PATENT OFFICE.

THOMAS N. RUSSELL, OF CHICAGO, ILLINOIS, ASSIGNOR TO CHICAGO-CLEVELAND CAR ROOFING COMPANY, OF CHICAGO, ILLINOIS, A CORPORATION OF DELAWARE.

UNCOUPLING DEVICE.

Application filed August 27, 1923. Serial No. 659,576.

This invention relates to railway cars and especially to uncoupling devices therefor. The main objects of the invention are to provide an improved form of uncoupler device and especially to produce a better form of connecting means or joint adapted to provide for limited flexibility in an uncoupler bar of the sectional cantilever type comprising two parts extending oppositely from a point adjacent to the fulcrum. Further objects are to provide a simplified and strong construction adapted for ready manufacture and maintenance at a low cost; and to provide such a device adapted for ready assemblage and interchange of parts.

An illustrative embodiment of this invention is shown in the accompanying drawings, in which:

Figure 1 is a fragmentary plan view of a car end showing the coupler and also the uncoupling means to which this invention relates.

Fig. 2 is a fragmentary end view of the lower part of the car body showing in elevation the device herein referred to.

Fig. 3 is a section on the line 3—3 of Fig. 4.

Fig. 4 is a section on the line 4—4 of Fig. 3.

Fig. 5 is a section on the line 5—5 of Fig. 3.

In the construction shown in the drawings, the car 1 and coupling device 2, including the lift pin 3, are shown substantially in accordance with the present usual construction. The medially supported uncoupling lever comprises two separate and detachable substantially aligned arms 4 and 5 which normally are operatively secured together and to the pivotally mounted box-like supporting connector 6. Arm 4 is the handle arm and arm 5 is the pin operating arm or lift member. The support or joint member 6 is carried by the horizontally facing pivot bracket 7, which is rigidly secured to the adjacent frame beam 8 of the car end and provided with a horizontal pivot 7'.

Said lever is normally disposed in a nearly horizontal position, and is rockable in approximately a vertical plane sufficiently to lift the knuckle lock 3 and so uncouple the cars whenever downward movement is applied to the handle arm 4. Said arm is preferably disposed mainly beneath the lowermost step 9 of the ladder on the end

of the car, so as to be protected from the accidental operation, as will be understood.

The arm connector or rocker frame 6 may well be made as a steel casting of rectangular shape. It is provided with a central transverse pivot hole 10 to receive the pivot 7', and with a pair of arm sockets 11 and 12 on the upper and under sides respective of the horizontal central partition 13 and partially intersecting said hole. The arms 4 and 5 overlap somewhat and are notched on their adjacent edges as at 14 and 15 respectively in registry with said hole 10 so as to be locked in place by said pivot 7' when the device is assembled for use. A cotter pin 16 in the perforation 17 of pivot 7' holds the box 6 in place against the bracket shoulder 18.

The upper aperture 11 receives arm 4 in substantially snug fitting relation so as to hold the arm rigidly, but the lower aperture 12 is longitudinally flared both horizontally and vertically in both directions from the middle where the arm 5 is secured against longitudinal movement by the pivot 7' in non-rigid relation. This accommodates the arm 5 to all normal operating movements of the car and coupling.

In order to prevent an unnecessary or undesirable degree of downward movement of arm 4, as in raising the knuckle lock 3, a stop shoulder 19 is provided on the back side of the connector 6 to engage or contact with the fixed shoulder 20 on bracket 7. The handle arm is thus definitely limited in its swing when pushed downwardly and thus tends to avoid accidents. Moreover the lift arm is prevented from swinging around too far and possibly striking the operator on the head. Said bracket 7 is held rigidly by bolts 21 in the bracket ear's 22, as will be understood.

Whenever it is desired to take the device apart, as for renewal of parts or for any other reason, the cotter 16 is removed. Then the connector 6 and lever arms carried thereby may be slipped off bodily from the pivot 7'. This releases the arms 4 and 5 which may then be removed. The reverse operation may be followed in assembling the device.

Although but one specific embodiment of this invention is herein shown and described, it is to be understood that numerous details of the construction shown may be al-

tered or omitted without departing from the spirit of the invention as defined by the following claims.

I claim:

- 5 1. An uncoupling device comprising in combination a joint member, a stationary fulcrum pivot whereon said member is oscillatably supported and a lever including a handle arm and an operating arm disposed 10 oppositely and having their adjacent ends arranged one above the other on opposite sides of said pivot and detachably secured to said member.
  - 15 2. An uncoupling device comprising in combination a connector, a stationary fulcrum pivot whereon said connector is oscillatably supported and a lever including a handle arm and an operating arm disposed oppositely and having their adjacent ends 20 detachably secured to said connector, the latter being apertured in one direction to receive said arms endwise in overlapped relation and in another direction to receive said pivot which is positioned horizontally, 25 said arm ends also being recessed on their adjacent sides to receive said pivot which serves to lock the said parts all together in effective relation.
  - 30 3. An uncoupling device comprising in combination a joint member, a fulcrum whereon said member is oscillatably supported and a lever including a handle arm and an operating arm disposed oppositely and having their adjacent ends detachably secured to said member, the latter being apertured in one direction to receive said arms endwise in mutually overlapped relation and in another direction to receive said fulcrum which is in the form of a pivot positioned 40 horizontally, said arm ends being notched on their adjacent sides to receive said fulcrum endwise between them, which serves to lock said parts all together in effective relation.
  - 45 4. An uncoupling device comprising a connector having a horizontal pivot receiving aperture and a pair of arm receiving apertures disposed crosswise of said aperture one above and the other below and intersecting said aperture, in combination with a supporting fulcrum pivot fitting in the corresponding aperture, a handle arm fitting 50
- in one of the other apertures and an operating arm fitting in the third aperture, said arms overlapping each other and being 55 notched to receive said pivot whereby they are locked in place when the device is assembled.
- 5 5. An uncoupling device comprising a connector having a horizontal pivot receiving aperture and a pair of arm receiving apertures disposed crosswise of said aperture one above and the other below and intersecting said aperture, in combination with a supporting fulcrum pivot fitting in the 60 corresponding aperture, a handle arm fitting snugly in one of the other apertures and an operating arm fitting loosely in the other arm aperture which is flared both ways from the center, said arms overlapping each other and being notched adjacently to receive said pivot whereby they are locked in place 65 against endwise movement when the device is assembled.
  - 70 6. An uncoupling device comprising a connector having a horizontal pivot receiving aperture and a pair of arm receiving apertures disposed crosswise of said aperture one above and the other below and intersecting said aperture, in combination with a supporting fulcrum pivot fitting in the corresponding aperture, a handle arm fitting in one of the other apertures and an operating arm fitting in the third aperture, said connector having a stop shoulder to limit 75 its movement in the uncoupling direction and the operating arm being fitted loosely in its aperture to accommodate the necessary lateral and vertical movements of said arm incident to car or coupler movements. 80
  - 85 7. In an uncoupling device comprising a connector having a horizontal pivot receiving aperture and an arm receiving aperture disposed crosswise of said pivot aperture, in combination with a supporting fulcrum pivot fitting in the corresponding aperture, and an arm fitting in the other aperture, said arm being notched to receive said pivot whereby it is locked in place when the 90 device is assembled. 95

Signed at Chicago this 23rd day of August, 1923.

THOMAS N. RUSSELL.
